UNITED STATES PATENT OFFICE.

ROBERT H. BAXTER, OF BROOKLYN, NEW YORK, ASSIGNOR TO DEFIANCE MANUFACTURING COMPANY, A CORPORATION OF MASSACHUSETTS.

DESIGN FOR A CALENDAR-STAND BASE.

58,867.

Specification for Design.

Patented Sept. 6, 1921.

Application filed May 24, 1921. Serial No. 472,267. Term of patent 14 years.

To all whom it may concern:

Be it known that I, ROBERT H. BAXTER, a citizen of the United States, residing at Brooklyn, New York, have invented a new, original, and ornamental Design for a Calendar-Stand Base, of which the following is a specification, reference being had to the accompanying drawing, forming part thereof.

Figure 1 is a plan view of a calendar stand base showing my new design;

Fig. 2 is a front elevation and Fig. 3 a side elevation of the same.

The holes shown in the base are for fastening the calendar pad on the base and constitute no part of my present invention.

I claim:

The ornamental design for a calendar stand base, as shown.

In witness whereof, I have hereunto signed my name.

ROBERT H. BAXTER.
